UNITED STATES PATENT OFFICE.

ADOLF ROBICZEK, OF VIENNA, AUSTRIA-HUNGARY.

SPLICING-BAR.

1,102,081.

Specification of Letters Patent. Patented June 30, 1914.

Application filed July 8, 1912. Serial No. 708,300.

To all whom it may concern:

Be it known that I, ADOLF ROBICZEK, a subject of the Emperor of Austria-Hungary, and residing at Vienna, Austria-Hungary, have invented certain new and useful Improvements in Splice-Bars, of which the following is a specification.

On running over the rail joints of a new track at first only slight vibrations are felt. This condition however lasts only as long as the wedging action of the splice bars produced by the tension of the fish bolts remains undiminished. The stressing of the rail joints results in a wear of the contact surfaces between the rails and the splice bars. Since however the material of the splice bars is considerably softer than that of the rails, the wear of the latter is appreciably less than the wear of the splice bars. Owing to this wear of the contact surfaces the splice bar on screwing up of the fish bolts penetrates always farther into its seat, and if the wedging action of the splice bar is to be maintained undiminished, it may penetrate so far that the fishing surface of the splice bar comes to the fillet between the rail head or the base flange and the web.

In the accompanying drawing: Figure 1 illustrates in outline a vertical cross section 30 of a rail joint as commonly constructed, portions of the rail and splice bar not required to illustrate the invention being omitted; Fig. 2 illustrates in outline a portion of a similar section of a joint embodying the 35 present invention; Fig. 3 illustrates a deformation of the splice bar that may occur with joints of ordinary construction and which is avoided by the present invention; Fig. 4 is a view similar to, and on substantially the 40 same scale as, Fig. 1 of the improved joint construction hereinafter particularly described; Fig. 5 illustrates the change in relation between the rail and splice bar of a common form of joint due to wear and adjustment; Figs. 6 to 8 illustrate the variations 45 or changes in relative position of a rail and splice bar, constructed according to the present invention, due to wear, etc.; Figs. 9 to 11 illustrate objectionable conditions and deformations that occur in joints of ordinary 50 construction and which are avoided by my invention.

In the several figures A—B represents the

axis of a rail, 1 a part of the rail head, 2 a portion of the base flange and 3, 4, respectively, the upper and lower sections of a splice bar.

Referring particularly to Fig. 1 the fishing surfaces of the splice bar are assumed as similar, so that the direction of motion of the worn splice bar is at right angles to the rail axis A—B. 5 and 6 are the points at which the filleting of the rail begins. 7, 8, 9, 10, 11 and 12 denote the original position, and 5, 13, 14, and 6 the final position of the splice bar. 15, 5 and 16, 6 is the extent to which the splice bar can penetrate into the fishing seat. After this distance the splice bar encounters a resistance at the fillets of the rails which becomes greater and greater the farther in the splice bar is forced. If the splice bar is kept in use after having reached the final position above referred to, its wedging action rapidly decreases, the result of which is that the vibrations on passing over the rail joints become greater and the rail ends and the fishing surfaces of the rails and splice bars subjected to hammering. The top surfaces of the rail ends thereby become deformed in the well-known manner, and this deformation always tends to increase. The fishing surfaces of both the splice bars and the rails are then subject to a considerably more rapid wear. The hammering action on the fishing surfaces creates, as can be observed in any old track, ridges or shoulders, and the rail head then assumes in the vicinity of the splice bar the form shown in Fig. 9. Such a ridge 25 (Fig. 9) is a great disadvantage for a reliable fishing with an unworn splice bar, for the reason that the ridge 25 cuts into the fishing surface or the outer fillet of the splice bar and makes it impossible for the latter to penetrate into its seating portion, whereby the wedging action of the splice bar is inoperative.

Another disadvantage of known types of splice bar is that on wear of the fishing surfaces of the splice bar a ridge projecting above this flat surface is formed, which bears against the outer edge of the rail head and prevents further penetration of the splice bar toward the web. A ridge or step 26 (Fig. 10) or 27 (Fig. 11) thus occurs when the fishing surface of the splice bar projects above

the fishing surface of the rail head, as for example in outer splice bars of the profile shown in Figs. 2 and 10, or in the cranked splice bar of the profile shown in Fig. 11, 5 and at the part which bears against the narrower rail head. A ridge 17 (Fig. 3) is formed when the height of the splice bar is too great or when in consequence of inequalities in the fishing surfaces, which is frequently the case, the splice bar does not penetrate sufficiently deep into the seating on screwing up the fish bolts. Such a ridge or shoulder considerably reduces the effectiveness of the splice bar from the beginning, and 10 the rail joint is then rapidly deteriorated by hammering. If the ridge is finally destroyed by repeated and powerful tightening of the fish bolts, the splice bar can penetrate at once a considerable distance into its seating, since 15 meanwhile it has been subjected to extensive hammering. The splice bar then soon attains its maximum penetration because in splice bars of known profiles the possible extent of uninterrupted penetration is very 20 25 small.

The form of cross section of splice bars according to this invention obviates all these disadvantages, and insures that the worn splice bar bears against only the flat fishing 30 surface of the rail and that the splice bar can penetrate the maximum possible distance into the seat without any diminution of the original wedging action corresponding to the degree to which the fish bolts are 35 screwed up. In Fig. 4 the profile of the splice bar according to the present invention is illustrated to an enlarged scale.

To prevent the formation of a ridge (Fig. 3) or a shoulder (Fig. 11), the splice bar is 40 provided at the part adjacent to the outer edge of the rail head, with a longitudinal bevel 28 (Fig. 4).

In an outer splice bar the upper flat fishing surface of which projects beyond the flat 45 fishing surface of the rail, the formation of a shoulder 26 (Fig. 10) is prevented by providing the fishing surface of the splice bar with a longitudinal groove 18 (Fig. 2). The bevel 28 (Fig. 4) or the groove 18 (Fig. 2) 50 also prevents a ridge 25 on the rail (Fig. 9) from working into the splice bar, whereby the substantial advantage is obtained that the improved splice bar exerts its full wedging action even with old rails having worn 55 fishing surfaces.

To enable the splice bar to have the maximum possible penetration into its seating while retaining the original wedging action corresponding to the tension of the fish bolts, 60 the surfaces of the splice bars facing the parts of the rail web adjacent to the head or base flange, are provided with a recess or depression 19, 20 (Fig. 4), or a groove (Fig. 8). The lower groove of the splice bar near 65 the base flange of the rail is symmetric with

the upper (Fig. 8). These depressions or grooves may be of different shape but the greatest advantage is obtained when they are of such form that the splice bar can penetrate into its seating until it abuts 70 against the web of the rail, without the original wedging effect of the splice bar undergoing any decrease. In the shape of the depressions 19, 20 or grooves, Fig. 8 care must be taken that, maintaining the necessary breadth of the flat fishing surfaces of the splice bar, the permissible wear, *i. e.* the wear experienced by the splice bar on penetrating from the original to the final position, is as great as possible. It is advisable 75 to form the depression or groove with such dimensions, that in the maximum penetration of the splice bar there is still a clearance to allow for any solid bodies which 80 may have penetrated into the cavity. 85

In Figs. 5, 6 and 7 are shown the extents to which the splice bar wears in passing from the original to the final position, and also the distance moved through by the splice bar, Fig. 5 relating to a splice bar of 90 known cross section, and Figs. 6 and 7 the splice bars according to the present invention. The known cross sections are indicated with dotted lines in Figs. 6 and 7.

In all the figures the wear surface is denoted by 21 and the distance moved through by the splice bar by 22. In Fig. 6 the contact point 23 taken in Fig. 5 as the starting point for the shoulder 19 is retained, while in Fig. 7 the depression or groove is broader 10 and therefore the fishing surface of some-what smaller area.

If instead of the depression a groove is provided as illustrated in Fig. 8, this groove can be so arranged that the fishing surface 1 of the splice bar is made broader. The projecting edge 24 can come into contact only with the flat fishing surface of the rail and is worn like all the gross hatched surfaces in Fig. 8 on penetration of the splice bar so that owing to this broadening the original wedging effort of the splice bar undergoes no decrease.

With flat rail fillets, the circumstance that in this case at the point 5 or 6 of Fig. 1 the filleting does not possess any appreciable deviation from the direction of the flat fishing surfaces of the rail, can be made use of in the construction of the depressions 19 and 20 (Fig. 4) or in the formation of the grooves (Fig. 8), to broaden the flat fishing surfaces of the splice bars.

The final position of the splice bars in the different figures is shown by chain dotted lines.

The cross section of splice bar according to the present invention affords considerable advantages. Owing to its bevel 28 (Fig. 4) or its groove 18 (Fig. 2) the splice bar will never encounter a resistance at the outer

rail head fillet, owing to a ridge 17 on the bar (Fig. 3), a ridge 25 (Fig. 9) on the rail, or a shoulder 26 (Fig. 10) or 27 (Fig. 11).

Splice bars of excessive length when the groove or bevel is suitably formed, have no disadvantageous results. Shortness of the splice bar is even less objectionable as will be evident by comparing the shaded wear surfaces shown in Figs. 5, 6, and 7, from which parallel strips of equal height should be assumed removed. The permissible wear of the improved splice bar, as will be seen on comparing the shaded areas 21 in Figs. 5, 6, and 7, is appreciably greater, the result of which is that the improved splice bars according to the invention have a much longer life than those of former types, and retain their wedging action undiminished. Another substantial advantage of the improved splice bars is that ordinary new and already used splice bars which have not been screwed in as far as the rail web, can be given their original wedging action by altering them to the cross section according to the present invention.

A splice bar with depressions 19, 20 or grooves (Fig. 8) so formed that the bar can be screwed in until it abuts against the rail web, without diminution in wedging effort also offers the advantage that from the position of such a splice bar in the fishing seat it can be at once observed whether the bar can still be kept in use; on the contrary with a splice bar of ordinary profile the clearance between the bar and the rail web must be determined by exact measurement to known whether such a splice bar is still exerting its original wedging effect. This

precaution is usually not observed with the result that the rail joint is subjected to hammering.

The improved splice bar according to the present invention has the further great advantage, that rail joints which have become deformed, can be improved.

Having now described my invention what I claim as new and desire to secure by Letters Patent is:—

1. A splice bar for said rails having longitudinal depressions or grooves at the inner corners of the fishing surfaces, adapted to enable the splice bar to penetrate into its seating until the inner side of the bar abuts against the rail web in spite of the presence of fillets in the rail.

2. A splice bar for railway rails having its inner corners and the upper outer corner cut away, whereby the bar may be adjusted inwardly until it contacts with the webs of said rails regardless of the presence of fillets on the rails and will uniformly contact with the heads and bases of said rails in all adjusted positions.

3. A splice bar for rails having a longitudinal groove at the inner corners of the fishing surfaces, so formed as to leave a projecting heel or edge increasing the area of the fishing surfaces, substantially as described.

In testimony whereof I affix my signature in presence of two witnesses.

ADOLF ROBICZEK.
